(57) **CLAIM**

The ornamental design for a children's mobile phone toy as shown and described.

DESCRIPTION

FIG. 1 is a perspective view of a part of children's mobile phone toy showing my new design;
FIG. 2 is another perspective view thereof;
FIG. 3 is a front view thereof;
FIG. 4 is a back view thereof;
FIG. 5 is a left view thereof;
FIG. 6 is a right view thereof;
FIG. 7 is a top plan view thereof; and,
FIG. 8 is a bottom plan view thereof.

The broken lines depict portions of the children's mobile phone toy and form no part of the claimed design.
